(57) **CLAIM**

The ornamental design for a cookpot, as shown and described.

DESCRIPTION

FIG. 1 is a perspective view of a cookpot in accordance with my design;

FIG. 2 is a front elevational view of the cookpot of FIG. 1; FIG. 3 is a rear elevational view of the cookpot of FIG. 1; FIG. 4 is a left side elevational view of the cookpot of FIG. 1;

FIG. 5 is a right side elevational view of the cookpot of FIG. 1;

FIG. 6 is a top plan view of the cookpot of FIG. 1; FIG. 7 is a bottom plan view of the cookpot of FIG. 1; and, FIG. 8 is a cross-sectional side view of the cookpot of FIG. 1, taken at section line 8-8 as shown in FIG. 5.

As shown in the depicted embodiments, the body of the cookpot has a continuous outer contour that is uninterrupted moving in a direction from the lid to the base of the body. The broken lines having consistent dash lengths (dash-dash-dash) represent portions of the cookpot that form no part of the claimed design.

The broken lines having inconsistent dash lengths (short dash-medium dash-short dash) represent boundaries of the claimed design. As shown in FIGS. 2, 3, and 8, the boundary lines are provided at an intersection between the body of the cookpot and the arms of the cookpot.
